US00D566329S

(12) **United States Design Patent** (10) Patent No.: **US D566,329 S**
Bagaric et al. (45) Date of Patent: ** Apr. 8, 2008

(54) **CONTAINER**

(75) Inventors: **Robert Bagaric**, Richmond (AU);
Steve Kepper, Richmond (AU);
Michael Staniford, North Sydney (AU)

(73) Assignee: **Philip Morris USA Inc.**, Richmond, VA (US)

(**) Term: **14 Years**

(21) Appl. No.: **29/236,470**

(22) Filed: **Aug. 16, 2005**

(51) LOC (8) Cl. **27-06**

(52) U.S. Cl. **D27/189**

(58) Field of Classification Search 206/236,
206/242, 245, 251, 252, 256-257, 259, 261-270;
D27/172, 183-192

See application file for complete search history.

(57) **CLAIM**

We claim the ornamental design for the container, as shown and described.

DESCRIPTION

FIG. 1 is a perspective view from one side of the container; FIG. 2 is a perspective view from the other side of the container;

FIG. 3 is a perspective view from one end of the container; FIG. 4 is a perspective view from the other end of the container;

FIG. 5 is a top view of the container; and,

FIG. 6 is a bottom view of the container.

The broken lines are shown for illustrative purposes only and form no part of the claimed design.
